UNITED STATES PATENT OFFICE.

DOMINICK CORDINO, OF PLYMOUTH, MASSACHUSETTS.

PROCESS OF MAKING METAL CASTINGS.

Application filed October 18, 1921. Serial No. 508,512.

To all whom it may concern:

Be it known that I, DOMINICK CORDINO, a citizen of the United States, residing at Plymouth, in the county of Plymouth and State of Massachusetts, have invented new and useful Improvements in Processes of Making Metal Castings, of which the following is a specification.

My invention relates to the method of making metal castings, and the object of my invention is to dispense with drilling and tapping screw threads in castings of all kinds, and especially in gas, oil and other stove castings.

It is well known that in fastening panels to stove doors, and in securing together fixtures of various kinds in stove and other castings for the purpose of concealing the fastenings on the face of the work, it is customary to cast a lug or lugs on the inside of one casting and to drill a hole in the lug and then tap a screw thread therein for the reception of a bolt or screw. These means are subject to a number of objections, and among them are, first, the danger of forcing the drill through the casting and thereby destroying or defacing it; secondly, of breaking the tap by not judging the distance accurately and driving it against the bottom of the hole. In some situations it is awkward to use the drill and tap because of difficulty of access to the particular position of the lug, all of which accentuates the risk of forcing the drill through the casting and breaking the tap, and also makes it difficult of drilling and tapping in a true direction.

My invention consists of a process of casting metals for the attainment of the foregoing objects, of certain novel devices to be employed in such process, and of the article produced by the process.

In the accompanying drawing, which illustrates some of the devices used in practicing my process, Fig. 1 is a perspective view of an attachment to the pattern used in forming the mold; Fig. 2 is a perspective view of a chaplet incorporated into the casting during the molding process; Fig. 3 is another perspective view of the chaplet and contents before casting; Fig. 4 is a plan view of a casting, molded by my process. Fig. 5 is a vertical section of one of the lugs 7, through the line X—X in Fig. 6, which is an enlarged perspective elevation of one of the lugs 7.

The first step in my process is to secure to

the pattern one or more attachments 16 like that shown in Fig. 1, made of any suitable material, preferably brass,—the number and location of these attachments being governed by the requirements of the particular casting. These attachments are in the form of a socket to receive the chaplet.

Fig. 4 illustrates a casting 8 designed to have another casting or panel secured to it at the four points indicated by the lugs 7. In molding such a casting as 8, there would be four of the attachments 16 secured to the pattern in the same relation, of course, to each other as the lugs 7, on the casting shown in Fig. 4. Before making the mold, a chaplet 9, shown in Fig. 2, made of sheet metal or other suitable material, is inserted in each attachment 16 on the pattern, but before doing so a screw threaded nut 10 is inserted in the upper part of the chaplet; as shown in Fig. 3, the hole in the nut coinciding with that in the top of the chaplet. Beneath the nut there is also deposited a core capable of becoming disintegrated by the molten metal, but remaining intact during the molding process sufficiently to prevent being displaced by the molten metal. Below the core 11 is a narrow space 12 as shown in Fig. 3. The chaplet containing the nut 10, and the core 11, is inserted in the attachment 16 in the pattern, with its open ends adjacent to the upright portions 13, 13 of the attachment 16, whereby the molding sand cannot enter the space 12 in the cabinet 9, during the making of the mold. The pattern is then placed in the molding sand in the usual manner for casting with the attachments 16 on the upper side of the pattern, and when the cope is raised from the drag, the chaplet 9 being light and loosely resting in the attachment 16, is lifted by the cope to which it adheres. The pattern is then removed from the drag, the cope is closed and the metal poured in the usual manner. The result is that lugs like the lug 7, are cast, in which the space 12 in the chaplet 9 is filled with metal which flows into the chaplet through the opening 17, and the core 11 is so disintegrated by heat that it is readily removed when the castings are rattled, leaving an open space 14, below the nut, as shown in Fig. 5.

Referring to the casting 8 in Fig. 4, each of the lugs 7 is provided with a screw threaded hole (see Fig. 5) to receive the screws or bolts 15 for the purpose of securing an

other casting thereto. It is obvious that by this method the holes in the lugs are accurately located, that all danger of defacing the casting by accidentally drilling through it is obviated, and as no tapping of the thread is required, there can be no breakage of taps. The screws or bolts 15 employed are selected with reference to their length so as not to extend to the bottom of the space 14 shown in Fig. 5. The screws or bolts 15 are readily removed when occasion requires separation of the castings for repairs or other purposes. A hole 18 is provided in the top of the chaplet to admit the bolts 15 and the nut 10.

While I have shown a chaplet made of sheet metal and prefer for economy to use that form with a nut inserted therein, it is obvious that the nut need not be a separate piece, but the chaplet itself may have the top sufficiently thick to admit of a screw threaded hole, and such construction would be the equivalent of the separate sheet metal chaplet and nut and within the scope of my invention.

While it would be more expensive and inconvenient to do so, it would be some advantage to use a chaplet having sufficient thickness of metal in the top to receive a screw threaded hole, and having a core and a space below it, so that the hole could be drilled and tapped after the casting was made, and it would involve a part of my invention; the risk of drilling through the casting or breaking the tap would be avoided or greatly diminished as the operator could usually discover by the feeling when the drill or tap had passed through the metal into the empty space.

My invention is applicable to castings of all shapes and sizes and to the employment of bolts and nuts of any variety of size or shape.

It is clear that not only is there a great saving in the production of the casting and an advantage in greater accuracy attained in the location of the bolts and screws, but also the equipment required for drilling and tapping is wholly dispensed with in the manufacture of the finished product.

What I claim and desire to secure by Letters Patent is:

1. The hereinbefore described process of casting metals, consisting of incorporating into the mold a chaplet adapted to receive a screw threaded hole in the top, and having a core in the upper portion of the chaplet and a space below the core with an opening into said space, and then pouring the metal into the mold and filling said space and closing said opening with the molten metal and causing the chaplet to form an integral part of the casting.

2. The hereinbefore described process of casting metals, consisting of incorporating into the mold a chaplet having a screw threaded hole in its top, and a core in the upper portion of the chaplet and a space beneath the core, and then pouring the molten metal into the mold and filling said space and closing said opening with the molten metal and causing the chaplet to form an integral part of the casting.

3. The hereinbefore described process of casting metals, consisting of incorporating into the mold a chaplet having a screw threaded nut located in the upper portion of the chaplet, a core located beneath the nut and a space beneath the core, then pouring the metal into the mold and filling said space and closing said opening with the molten metal and causing the chaplet to form an integral part of the casting.

4. In a metal casting a chaplet having a screw threaded hole in the top, combined with a chamber located within the chaplet and having no opening in its bottom through the casting.

5. In a metal casting a chaplet having a screw threaded nut located in the top, combined with a chamber within the chaplet and beneath the nut, and having no opening in its bottom through the casting.

In testimony whereof I have hereunto set my hand in presence of two subscribing witnesses, this 6th day of October, 1921.

DOMINICK CORDINO.
